UNITED STATES PATENT OFFICE

CARMELO FURNARI, TONY BASILE, AND ROSS SCIOTTO, OF ALTOONA, PENNSYLVANIA

RAIL JOINT

Application filed August 15, 1929. Serial No. 386,136.

This invention relates to improved rail joints, characterized by certain refinements and improvements in construction such as serve to provide a structure which is a distinct contribution to the art.

The invention is predicated upon the provision of notches of a peculiar design in the adjacent ends of the web portion of a pair of complementary rails, wherein these notches 10 serve in producing what may be designated as a key slot, and a key of a corresponding shape is fitted into this slot in such a way as to securely fasten the rails together and at the same time to compensate for expansion 15 and contraction from weather conditions.

A feature of novelty is predicated upon this key connection which is placed in the slot at right angles to the web portion and which is of a thickness equal to the web portions and 20 therefore flush with said web portions, together with a pair of complementary slidably mounted fish plates on opposite sides for maintaining the key in place, said fish plates being retained in position by special retaining bolts or members, in order to provide a 25 complete structure which eliminates entirely the employment of conventional fasteners, such as bolts and nuts.

It is our aim to generally improve upon 30 rail joints by providing one which is further characterized by reasonable simplicity and economy in construction and arrangement, the arrangement being such as to insure efficient results, to expedite connecting of the 35 rails, and placement of the parts, and to otherwise fulfill the requirements of a structure of this class.

Other features and advantages will become more readily apparent from the following description and drawings.

In the drawings:—

Figure 1 is a side elevation of a pair of rail-ends embodying the fastening means constructed in accordance with the present invention.

Fig. 2 is a slightly enlarged side view of the rail ends showing the double dove-tailed key in the correspondingly shaped slot, the fish plates being removed for clearness.

Fig. 3 is a horizontal or longitudinal sec-

tion taken approximately upon the plane of the line 3—3 of Fig. 1.

Fig. 4 is a transverse vertical section on the line 4—4 of Fig. 1.

Fig. 5 is an enlarged perspective view of one end portion of one of the rails.

Fig. 6 is a perspective view of the especially designed coupling key.

The rails are distinguished by the reference characters 7 and 8 respectively, although each rail end is the same in construction. For instance, by referring to Fig. 5, it will be seen that each rail comprises the base flange 9, the web portion 10, and the ball or head 11. In this instance, the head or ball is formed 65 on its under side adjacent each end with longitudinally extending ribs 12 arranged in spaced parallelism with the web and forming longitudinal slideways.

Moreover, the base flange is formed with 70 correspondingly disposed shoulders 13 defining complementary slideways. Then too, the web portion is formed with a notch 14 which opens through each end, and which has its inner end of the shape shown at 15 to form 75 what may be designated as a dove-tail shaped opening. When the two rail ends are placed in abutting relation, the complementary notches define a longitudinal key slot.

Adapted to be fitted in from the sides in 80 the slot is the key 16. This comprises a rectangular central portion 17 having duplicate dove-tailed end portions 18. Thus the body portion extends into the complementary notches 14 and the end portions 18 are fitted 85 into the correspondingly shaped end portions 15 of the slots, thereby bridging the space between the rail ends as shown plainly in Fig. 3.

It will be noted that the key is of a thickness corresponding to the thickness of the web and therefore is flush with the opposite faces of the web. On opposite sides, I provide a pair of duplicate fish plates 19 and these are of rectangular configuration and of 95 a length commensurate with the combined lengths of the aforesaid slideways in the rail ends 7 and 8. In fact the fish plates bridge the joints between the rail ends and cover and conceal the key and key slots.

Each fish plate is of the cross sectional configuration shown in Fig. 4. Here it will be observed that it has upper and lower longitudinal ribs 20 and 21 which fit into the complementary slideways. Formed on the web of the rail end 7 on one side and formed on the opposite side of the complementary rail 8 is a stop lug 22 against which the complementary fish plates slide. After the fish plate is slid in, it is retained by a special sliding latch member 23 having an operating lug 24. This lug projects outwardly sufficiently far to permit it to be struck with a hammer and driven down into the keeper notch 25 in the base flange, as indicated plainly in Fig. 5.

The latch 24 is of dove-tailed cross sectional shape, as seen plainly in Fig. 3. Thus it is securely held in place. In practice, the notched rail ends are brought together in the usual way, thus defining the elongated key slot. Then the double-ended or dove-tailed key member is placed in the slot in a direction at right angles to the web portions of the rails. The dove-tailed ends are slightly smaller than the corresponding portions of the slot to allow for expansion and contraction. No bolts or other fastening means are required in shoving this key in place.

Then, the fish plates are slid into their respective slide grooves or slideways against the complementary abutments. Then the latches are driven down into their respective keeper seats, thus securely maintaining the fish plates in place as well as the key. Consequently, an effective joint is had and no special fastening devices or objectionable bolts, nuts or the like are required.

A careful consideration of the description in connection with the drawings will enable the reader to obtain a clear understanding of the invention, the method of use, and the features and advantages thereof. Therefore, a more lengthly description is regarded as unnecessary.

45 Minor changes in shape, size, and rearrangement of details, coming within the field of invention claimed may be resorted to in actual practice if desired.

Having thus described our invention, what 50 we claim as new is:—

1. In a rail structure of the class described, a pair of complementary rails having their web portions cut out to provide a longitudinal key-slot, a removable retaining and coupling key arranged in said slot for joining the ends of said rails together, and slidably mounted retaining plates associated with the rail ends and disposed on opposite sides of the web portion for maintaining said key within its slot, and means on the web portions of said rail ends for limiting the sliding movement of the complementary plate in one direction, said rail ends being provided with latch seats, and 55 slidable retaining latches carried by the

plates and cooperable with said seats for holding the plates in position.

2. In a rail joint construction of the class described, a pair of complementary rails having their adjacent ends disposed in abutting relation and having their web portions formed with especially designed notches defining an elongated key-slot, the opposite end portions of said slot being of dove-tailed configuration, a key arranged in said slot and having dove-tailed end portions fitted into correspondingly shaped end portions of said slot, a pair of slidably mounted fish plates mounted on the rail-ends in a position to bridge the joint between said ends, said fish plates being of a size to completely cover and conceal the key, and retaining latches for said fish plates.

3. In a rail joint construction of the class described, a pair of abutting rails having their complementary web portions formed with a key-slot, a removable key in said slot coupling said rails together, the head and base portions of said rails being formed with upper and lower grooves constituting slideways, a stop abutment at one end of each pair of slideways, a latch seat on the opposite end of each pair, a pair of fish plates disposed on opposite sides of the web portion, and slidably in said slideways, the fish plates being adapted to engage the abutment and being provided with transversely disposed slidably mounted latches, each latch having an operating lug and said latches being located for removable reception in said keeper seats.

In testimony whereof we affix our signatures.
